JONAS BIKOFF,

INVENTOR.

BY: Julian J. Wittal,
his attorney.

11 produces a closed contracted form which will not allow the wrist to be inserted in it, but which can be easily opened and closed by the fingers, so that it may be used as a bracelet or as a belt. It will be particularly useful for children, as it has a strong belt which can be easily adjusted, and which is made of a flexible material which can be easily bent and straightened.

UNITED STATES PATENT OFFICE

2,457,200

FOLDABLE BRACELET CATCH

Inventor: Jonas Bikoff, Brooklyn, N. Y.

Application February 26, 1947, Serial No. 730,980

2 Claims. (Cl. 24—71)

1

This invention relates to closure or locking means for bracelet chains and the like, and has for its main object to provide a device of this type which will open up into an expanded condition or close into a much shorter contracted condition, in an easy, efficient manner.

Another object of this invention is to provide a device as indicated, which will be of the foldable type and which will have novel efficient means to lock the folded members to one another when it is desired to contract the bracelet or the like, or to release them from one another and open them up when it is desired to expand the bracelet.

Still a further object of this invention is to provide a device as characterized hereinbefore, wherein the folding and locking into contracted position, as well as the opening up and expanding of the same, may be done in an easy, quick manner, without the use of the fingernails or special protuberances or other devices on the foldable catch which are necessary in the expandable and foldable catches for bracelets now in use, and which are very undesirable features therein.

Still another object of this invention is to provide a device of the desirable characteristics indicated, which, in closed position, may be easily further contracted for a final adjustment.

Other objects of this invention will be partly apparent as the specification of the same proceeds, or partly pointed out therein.

In the drawings forming a part of this specification and accompanying the same:

Fig. 1 is a perspective view of my complete bracelet catch or lock in open position, parts of the first member thereof being separated for clearer view of the same;

Fig. 2 is a fragmentary perspective view of said first member, the three parts thereof being assembled as they are used in my folding catch, and this figure being on a much larger scale than Fig. 1;

Fig. 3 is a longitudinal sectional view of my folding bracelet catch in a closed, contracted position, and

Fig. 4 is a transverse sectional view of the same, the section being taken on the line 4—4 of Fig. 3.

Referring now to the drawings more in detail by characters of reference, my foldable bracelet catch in the embodiment shown, is composed of five members, generally indicated by the numerals 10, 11, 12, 13, 14, and, as has been mentioned, the first member 10 is shown with its parts assembled in the position as used in my foldable catch in Fig. 2, while in Fig. 1 the base frame 10a thereof is only shown as attached to the next folding

member 11, and the two other parts 10b and 10c of said first folding member 10 are shown separately.

Said first foldable member 10 has a base element 10a which is U-shaped in cross section, having the bottom 15 and the two side flanges 16. Into said U-shaped base 10a is set a double acting spring member, generally indicated by the numeral 10b, which is formed by a thin sheet metal plate 17 having the shape indicated in the figures, so that it may fit over the bottom 15 of the base member 10a, and in the center thereon a spring tongue 18 is separated from its material as by the left hand shorter axial slot 19, the right hand somewhat longer slot 20, and the transverse end slot 21, said spring tongue 18 normally being bent somewhat upwardly out of the plane of the base plate 17.

Four upstanding spring ears 22 are arranged adjacent to the four corners of the plate 17, but somewhat spaced apart therefrom, each ear having an inwardly turned bead 22a.

The next folding member or link 11 is in the shape of a frame, having outwardly turned pins 23 by which it is pivoted in the respective ends of the flanges 16. At the other front end of the first link member 10a a small cross bar 24 is arranged spaced apart from the bottom 15 thereof, while the inner end 11a of the pivoted second link member 11 is also spaced apart from the bottom plate 15 to a similar extent. The spring member 10b will be inserted into base member 10a in the position shown in Fig. 2, its bottom plate 17 resting over the bottom 15 of said member, and its respective ends 25 and 26 being placed underneath the cross bar 24 and the inner marginal rotating end 11a of the second link member 11, respectively, as indicated in Fig. 2, whereby the spring member 10b is permanently and reliably secured into the channel base member 10a, the upstanding ears 22 preferably frictionally engaging the respective flanges 16.

The third element 10c of the first link member 10 is a slotted grid plate, and it will be placed underneath the spring member 10b between the same and the bottom 15 of the base member 10a.

As indicated in Figs. 1 and 3, one end 27 of the bracelet chain 28 will be hooked in a pivoted manner into the first narrow slot 29, and it also will be obvious that the grid plate 10c may slide inwardly and outwardly on the bottom 15 of the member 10, as indicated by the double arrows 30 (Figs. 2 and 3), whereby the length of the bracelet may be delicately adjusted.

55 A downwardly projecting ear 31 is struck out

of the material of the spring tongue 18, and, when the device is in an open position as indicated in Fig. 2, the grid member 10c may freely slide inwardly or outwardly under said spring tongue 18 and its downwardly projection 31. However, when the spring tongue 18 is pressed downwardly or inwardly into the device, which will be the case when the device is closed, as will be more fully explained presently, then the spring tongue projection 31 being curved inwardly will permit only an inward movement of the grid plate 10c but prevent an outward movement thereof since then one of its slots 32 will be caught by the inner edge 31a of the ear 31. In a word, when the device is closed, the grid plate 10c may be pushed inwardly to a desired extent, but will be locked in any of its inward positions wherethrough the bracelet may receive its final adjustment. An upward projection or button 33 is struck into the material of the grid plate 10c adapted to slide inwardly and outwardly in the slot 20 of the spring plate 10b, said button serving as a limitation for the outward movement of the grid plate 10c.

The second link member 11 is in the form of a frame pivoted in the inner ends of the flanges 16, as indicated at 23. This link member and all the further ones are narrower than the first link member 10, so that they may be folded one over the other inside of said flanges and into the space within said first member, as will be explained hereinafter.

The third link member 12 is somewhat narrower than the second link member 11, and is in the form of an appropriately shaped plate 34 being hingedly secured into the frame 11 adjacent to its further end, as indicated at 35.

The fourth link member 13, again, is in the shape of a frame of about the same width of the link member 11, and the curved plate link member 12 is hinged adjacent to the inner end of said frame, as indicated at 35. The last link member 14, is again, in the shape of a channel or flange plate of U-shape cross section, similar to the first one, but also being somewhat narrower so as to be adapted to be folded thereinto. It has a bottom plate 36 and two longitudinal flanges 37. An inwardly projecting indentation or small rounded channel 38 is pressed into each flange 37. Said last link member 14 also will have an inwardly turned transverse terminating flange 39, which may have a cross pin 39a formed in its material, into which may be pivotally secured the other end 40 of the bracelet or chain 28, as will be understood.

The use and operation of my device will be understood by those versed in the art from the herein description. However, I want to add the following further remarks relating thereto.

When it is desired to close my bracelet catch and thereby shorten the bracelet, the various link members will be pushed one over the other and all of them into the first member 10. It will be understood that in the usual use of the bracelet, this member will be the outer one or top member, and all the members are appropriately curved so that the catch should conform to the curve of the wrist, when in a closed position.

When closing the device, first the frame member 11 will be turned on its pivot 23, as indicated by the arrow 41, into the first member 10 and between its flanges 16, whereupon the curved plate member 12 will be folded thereover, as indicated by the arrow 42, then the third member 13 will be folded, again, in the same direction as the folding of the second member 11, and as indicated

by the arrow 43, and, finally, the last member 14 will be folded, as indicated by the arrow 44, on its pivot 44a.

The user now will exert a slight pressure on the opposite end members of the folded device, as indicated by the arrows 45 (Figs. 3 and 4), which will cause the flanges 37 of the last member, which in this arrangement, will be the innermost or bottom member of the folded device to snap between the upstanding spring ears 22 of the first member 10, whereby the catch will be closed in a reliable but still easily releasable manner.

It will be seen that such a pressing of the last member 14 into the first member 10 will cause the springs 22 to be somewhat flattened out, their free ends 22b sliding on the flanges 16 until their inward indentations 22a will snap into the respective inward indentations or channels 38 of the flanges 37 of the bottom or innermost link member.

Such an inward movement of the last member 14 will press the curved plate member 12 inwardly. An inward or downward indentation 46 is provided in the inwardly curved portion of the plate 34 which will press the spring tongue 18 towards the plane of its plate 17 whereby its projection 31 will be placed into the path of the grid plate 10c, and will permit only an inward adjustment thereof and secure or lock it against any outward movement, as has been explained hereinbefore.

As has been mentioned, when the bracelet is worn and is closed, the outermost member will be the first member 10a, and the position thereof will be as indicated in Fig. 3, such catches usually being on the inside of the wrist of the wearer. When it is desired to open up my catch, the wearer, as usual, will turn his wrist upwardly and simply catch the outermost member 10 between his thumb and finger by the two flanges 16, and exert a slight upward pull thereon, as indicated by the arrow 47 in Figs. 3 and 4, wherein, of course, the position of the catch is indicated in the reverse manner as normally worn.

A comparatively slight pull on the top member 10 in the direction of arrow 47 will cause said member to start opening up on its pivot 23, and continuing said pull thereon will cause all the other members to unfold and open up on their respective pivots, as indicated in Fig. 1.

It will be seen that my bracelet catch may be closed in a very simple manner by folding the members one upon the others and exerting a pressure on the top member, and, similarly, it may be opened up in an extremely simple manner by catching the top member and lifting it off the bottom member and thereby unfolding the same and all the intermediate members.

While I have shown a preferred embodiment of my invention, I am aware of the fact that changes and variations may be resorted to in its elements, constructions, and combinations, and I reserve my rights to said changes and variations which are within the spirit of this specification and the scope of the claims hereunto appended.

What I claim as new and want to protect by Letters Patent of the United States is:

1. In a bracelet catch, having pivoted link members adapted to be folded one over the other when the catch is in a closed contracted position, or to be strung out into a chain-like arrangement when the device is expanded, the combination, of two oppositely placed channel U-shaped end link members, one forming the bottom member,

the other the top member, of the catch when the same is in a closed position, said end members remaining in said opposite positions when closed upon one another, the bottom member being somewhat narrower and adapted to fit with its flanges between the flanges of the top member, a spring plate secured inside of said top member, spaced apart from the base plate portion thereof, an inwardly and outwardly slidable grid plate between said spring plate and the base of said U-shaped top member, one end of the bracelet chain being secured to said grid plate whereby the length of the chain may be adjusted by the movements of said grid plate, a spring tongue struck out of said spring plate and curved away from said grid plate, an indentation on said spring tongue, means on one of the intermediate folding members, adapted to bend said spring tongue towards said grid plate when the catch is closed, the indentation on said tongue then engaging the slots in said grid plate, said indentation permitting an inward movement of said grid plate but locking the same against an outward one, by engaging a respective slot therein.

2. In a bracket catch, having pivoted link members adapted to be folded one over the other when the catch is in a closed contracted position, or to be strung out into a chain-like ar-

rangement when the device is expanded, the combination, of a spring plate secured inside of one end member, spaced apart therefrom, an inwardly and outwardly slidable grid plate between said spring plate and said end member, one end of the bracelet chain being secured to said grid plate whereby the length of the chain may be adjusted by the movements of said grid plate, a spring tongue struck out of said spring plate and curved away from said grid plate, an indentation on said spring tongue, means on one of the intermediate folding members, adapted to bend said spring tongue towards said grid plate when the catch is closed, the indentation on said tongue then engaging the slots in said grid plate, said indentation permitting an inward movement of said grid plate but locking the same against an outward one, by engaging a respective slot therein.

JONAS BIKOFF.
